UNITED STATES PATENT OFFICE.

HENRY F. SCHMIDT, OF SWARTHMORE, PENNSYLVANIA, ASSIGNOR TO THE WESTINGHOUSE ELECTRIC & MANUFACTURING COMPANY, A CORPORATION OF PENNSYLVANIA.

DISHWASHING MACHINE.

Application filed August 23, 1921. Serial No. 494,506.

This invention relates to pumps and more particularly to motor-driven propeller pumps having a fairing cone and guide vanes in the discharge portion thereof, and it 5 has for an object to provide a fairing cone and guide vanes of the character designated which may serve in the capacity of a shut-off valve for the pump as is desirable with certain types of washing machines. It has for 10 a further object to provide apparatus which shall effectively prevent fluid leakage between the pump and the motor. The above and other objects will be more manifest from the following specification and drawings, in 15 which

Figure 1 is a diagrammatic view, partially in section and partially in elevation of a washing apparatus embodying my invention; Figure 2 is a detail view, in section, of 20 a portion of the apparatus shown in Figure 1, and Figure 3 is a view, in section, taken on the plane III—III of Figure 2.

The present invention relates to a motor driven propeller pump particularly adapted 25 for emptying a fluid receptacle. As shown, the fluid receptacle may be a dish-washing machine and, for brevity in this specification, may be hereinafter referred to as such. Apparatus constructed in accordance with 30 the present invention is particularly adapted for use with mechanical washing machines of the character forming the subject matter of my co-pending application, Serial No. 307,705, filed June 30, 1919, and assigned to 35 The Westinghouse Electric & Manufacturing Company. In washing machines of this type, it is desirable to effect both the washing operation and the emptying of the receptacle by means of the motor operating the machine. This result is obtained in the present 40 instance, by embodying the fairing cone and guide vanes in the form of a valve of the butterfly type which is preferably eccentrically pivoted in the discharge portion of the pump 45 and located adjacent to the propeller operating therein. This arrangement permits the pump and valve to occupy a small space without detriment to the efficiency of the apparatus. Thus, the length which would 50 ordinarily be occupied by the guide vanes is saved, this being particularly desirable in the vertical design of pump shown. The vanes and the cone hub portion associated there-

with function as a shut-off valve when the machine is emptied of waste fluid by the 55 pump operating the machine.

Referring to Figures 1 and 2 of the drawing for a more detailed description of apparatus embodying my invention, I show a washing machine in which 10 indicates a 60 washing receptacle with a lid 11 and supports 12. Washing fluid may be supplied to the washing machine at the lower portion thereof through a nipple 13. The washing fluid is distributed to the utensils to be 65 washed by means of a centrally disposed vertical spray pipe 14. Secured to the bottom of the casing 10 at the lower portion thereof and receiving the conduit 13, is a specially 70 designed cup-shaped receptacle 15. The receptacle 15 has provided at the central portion thereof a hollow casing portion 16 supported by ribs 17 and the nipple 13, all of which may preferably be made in one casting. The arrangement of the receptacle is 75 such that the central portion forms a pump casing having the inlet portion open to the receptacle 15 and the discharge portion communicating directly with the spray pipe 14.

The lower portion of the receptacle 15 is 80 arranged to receive the motor and pump parts which are preferably of the propeller type. As shown, a propeller 18 is located in the inlet portion of the casing 16, said propeller being supported by a motor casing 85 18', the motor being directly connected to the propeller by a shaft 19. That portion of the motor casing extending into the cup-shaped receptacle is provided with vanes 20 to cause an even flow of fluid to the propeller 18. The motor casing 18' is detachably secured 90 to the lower portion of the cup-shaped receptacle 15 in any suitable manner, as for example, by thumb screws 21. The above arrangement permits the pump and motor 95 parts to be readily moved for the purpose of cleaning and repair. That portion of the motor casing 18' carrying the propeller shaft 19 is provided with a space 21' to accommodate a suitable packing for the shaft. As 100 shown, felt washers 22 are placed in the space 21' and held in place by a spring 23 and a nut device 24. To prevent seepage of fluid to the motor and to provide ample lubrication, the felt washers 22 are impregnated 105 with graphite or other suitable lubricant.

To prevent further fluid leakage from entering the motor, I mount a shield disc 25 on the propeller shaft 19 so that any fluid leaking past the felt washers will be thrown off and drained out through an opening 26 provided in the motor casing.

Located in the discharge portion of the pump casing 16 is a guide vane structure 30 mounted in an off-set position and embodying a fairing cone 31 adapted to prevent eddy currents and to facilitate the handling of large quantities of fluid. As shown in Figure 3, the four vanes may be considered to be disposed about a common axis and at substantially 90° apart, and to be provided with a conical hub portion 31. The vane structure is pivoted transversely of the fairing cone, as indicated at 32 and is operated by a suitable resilient means 33, Fig. 1, which is adapted to maintain the fairing cone 31 in the vertical position, as shown. The resilient means may be operated in any suitable manner as, for example, by a cable 35.

Having thus described an apparatus constructed in accordance with my invention, the operation thereof is as follows: The washing receptacle 10, may be filled with washing fluid in any manner or from any convenient pressure source through the nipple 13 and the washing operation is effected by forcing the fluid through the spray pipe 14 with sufficient force to enable the small jets to loosen food particles adhering to the utensils in the washing machine. The washing fluid drains down to the cup-shaped receptacle 15 and is repeatedly pumped through the spray pipe 14 until the utensils are clean. When the washing operation is completed, the cable 35 is pulled slightly, and the vane structure 30, being eccentrically pivoted, the pressure of fluid delivered by the pump is unequally distributed on the vane surface and immediately causes the vanes 30 to rotate and to close the entrance to the spray pipe 14, thereby increasing the discharge pressure of the pump. Thus the waste fluid is expelled from the receptacle through the nipple 13 and when empty, the resilient device 33 returns the valve 30 to its normal position to function as a fairing cone and guide vanes. The above operation may then be repeated, using clean water to effect the rinsing of the washed utensils. The arrangement described is particularly desirable as it enables the washing machine to be readily emptied and filled without handling the washing or waste fluids used in the washing and in rinsing operations.

While I have shown my invention in but one form, it will be obvious to those skilled in the art that it is not so limited but is susceptible of various other changes and modifications without departing from the spirit thereof, and I desire, therefore, that only

such limitations shall be placed thereupon as are imposed by the prior art or as are specifically set forth in the appended claims.

What I claim is:

1. In combination in a washing machine having a collecting chamber for washing fluid and a vertically disposed pump casing within the collecting chamber, and a detachable motor and propeller unit supported by the bottom of the collecting chamber in such a manner that the propeller operates within the pump casing to pump a fluid from the collecting chamber.

2. In a washing machine having a washing chamber with a spray pipe therein, the combination of a collecting chamber communicating with the washing chamber and having an interior chamber communicating with the spray pipe, pump means supported by the collecting chamber and extending into the interior chamber portion thereof, a conduit passing through the collecting chamber and communicating with the interior chamber and a fairing cone for the pump eccentrically mounted within the interior chamber and arranged to close the passages between the inner chamber and the spray pipe so that fluid from the collecting chamber may be expelled through the conduit to empty the washing chamber.

3. In a washing machine having a washing chamber and a vertically arranged spray pipe therein the combination of a collecting chamber having a vertically arranged inner casing supported in the collecting chamber, said inner casing arranged to communicate directly with the spray pipe and the collecting chamber, motor driven pump means supported by the collecting chamber and located in the inner casing, a conduit passing through the collecting chamber and communicating with the inner casing, and means pivoted in the inner casing and adapted to function as a fairing cone and guide vanes for the pump during the washing operation and a shut-off valve to direct waste fluid through the conduit for emptying of the washing machine by the motor pump means.

4. In a washing machine, in combination, a washing chamber, a collecting chamber for receiving water from the washing chamber, means constituting a passageway through which water is delivered from the collecting chamber to the washing chamber, means for pumping water through the passageway, a valve for closing the passageway means, means for manually initiating the movement of the valve toward closed position, said valve being disposed for operation by water moved by the pumping means when movement of the valve has been initiated.

5. In a washing machine, in combination, a washing chamber, a collecting chamber for receiving water from the washing chamber, a communicating element through

which water is delivered from the collecting chamber to the washing chamber, means for pumping water through the communicating element, a valve for closing said element, 5 means for manually initiating the movement of the valve toward closed position, and means for automatically restoring the valve

to initial position when the collecting chamber has been emptied.

In testimony whereof, I have hereunto 10 subscribed my name this 28th day of July, 1921.

HENRY F. SCHMIDT.
